UNITED STATES PATENT OFFICE.

EUGÈNE SCHNEIDER, OF PARIS, FRANCE, ASSIGNOR TO SCHNEIDER & CIE, OF PARIS,
FRANCE, A LIMITED JOINT-STOCK COMPANY OF FRANCE.

PLASTIC OBTURATOR FOR GUN BREECHES.

Application filed June 9, 1921. Serial No. 476,301.

To all whom it may concern:

Be it known that I, EUGÈNE SCHNEIDER, a citizen of the Republic of France, resident of Paris, France, have invented new and useful Improvements in Plastic Obturators for Gun Breeches, which invention is fully set forth in the following specification.

The subject of the present invention is an improvement in plastic obturators for the breeches of guns, comprising, in the known way, a pad of plastic material contained in a wire gauze or other bag, which is held between split metal rings, having substantially right triangular cross sections.

Fig. 1 of the accompanying drawing is a diametrical section along an axial plane of an obturator of this kind. In this figure, A represents a ring of plastic material contained in a bag B of wire gauze or some other suitable material. The pad thus enveloped is held between split metal rings C, D of steel or other suitable metal; these rings have a transverse section on a radial line substantially the shape of a right angled triangle. The hypotenuse sides c of the outer rings, and d of the inner ring bear against the pad, while the side c' of the outer rings bear against the wall of the breech, and one of the sides d' of the inner ring bears against the spindle of the movable head.

One of the rings of the ordinary obturators is shown in detail, in sectional elevation, Fig. 2, in corresponding partial plan Fig. 3, and in section along 4-4 of Fig. 3, Fig. 4.

As shown by these Figs. 2, 3 and 4, the cleft in the rings is obtained by cutting the ring along an oblique plane P from a line p along one of the short sides c' of one of the triangular sections of the ring. The cleft is thus bordered by a line p, two curves p¹, p² which are the intersections of the plane of section with the bearing surfaces c, c' of the ring and a point p³ inwardly situated, which tends to sink into the envelope B of the pad.

In practice the bag is often punctured by the retaining rings thus split and, consequently, a leakage of plastic material occurs.

This disadvantage is prevented in the present invention, by a special method of splitting the expandable rings C and D.

A ring split according to the present invention is shown in detail in Figs. 5 to 8.

Fig. 5 is a sectional elevation of the new ring corresponding with the section Fig. 2 of an ordinary ring.

Fig. 6 is a corresponding partial plan.

Fig. 7 is a partial transverse section along 7-7 of Fig. 6.

Fig. 8 is a perspective view with a part broken away.

In these figures, the rings are substantially right triangular in cross section, the same being split diagonally toward their hypotenuse or base sides from the apex edges opposed to said sides. The hypotenuse or base sides of the rings bear against the outer and inner inclined edge portions of the ring shaped plastic body, and when the obturator is assembled with the breech block and the latter is closed, the sides c' and d' bear against the wall of the breech and the spindle of the mushroom head respectively. The rings are preferably split on curved planes and the radially-overlapping ends of the same thus have opposed curved triangular faces 2, the bases of which abut the plastic body. One of the radially overlapping ends of each ring terminates in a straight edge 3 contacting with the plastic body and the other terminates in the point p³ which bears against a portion of the ring interposed between said point and the plastic body. A transverse section through the radially-overlapping ends of any one of the rings intersects the same on a straight line parallel to the hypotenuse or base side while a similar section through the overlapping ends of a ring such as illustrated in Figs. 1 to 4 intersects the same on a line 1 parallel with an outer side of the ring.

With the new method of splitting the rings, their laps meet on the plastic substance along a line, instead of meeting in a point whereby penetration of the bag by the ends of the overlapping portions and resultant leakage of plastic material, is prevented.

I claim:

1. An obturator comprising a plastic pad, and a diagonally split ring triangular in cross section the base side of which bears against said pad, the inner end of said ring terminating in a straight edge contacting with the pad and disposed substantially at right angles to the edges of said base side.

2. An obturator comprising a ring shaped

- plastic pad and rings triangular in cross section, the base sides of which bear against outer and inner edge portions of said pad, each of said rings being split diagonally toward the base side from the apex edge opposed thereto. 30
3. In an obturator, the combination of a body including a bag and a plastic pad therein, and a ring triangular in cross section the base side of which bears against an edge portion of said body, said ring being split diagonally toward the base side from the apex edge opposed thereto. 35
4. In an obturator, the combination of a plastic pad having an inclined edge portion at one side thereof, and a ring substantially right triangular in cross section the hypotenuse side of which bears against said inclined edge portion, said ring being split diagonally toward the base side from the apex edge opposed thereto. 40
5. In an obturator, the combination of a ring shaped plastic pad having outer and inner inclined edge portions, and rings substantially right triangular in cross section the hypotenuse sides of which bear against said outer and inner inclined edge portions, each of said ring being split diagonally to- 45
- ward the hypotenuse side from the apex edge opposed thereto. 50
6. An obturator comprising a pad and a ring bearing against the same, said ring being split diagonally to provide overlapping ends having opposed curved triangular faces, the base of the innermost triangular face being disposed adjacent to said pad. 55
7. An obturator comprising a plastic pad and diagonally split rings triangular in cross section the base sides of which bear against opposed edge portions of said pad, the inner end of each ring terminating in a straight edge, contacting with the pad and disposed substantially at right angles to the edges of the hypotenuse side. 60
8. An obturator comprising a plastic pad and a ring triangular in cross-section the base side of which bears against said pad, said ring being split diagonally toward the base side from the apex edge opposed thereto. 65

In testimony whereof I have signed this specification. 50
